INTERMITTENTLY OPERATING ELECTRICAL DEVICE

Charles Ludwig Hanel, Jackson Heights, N. Y., assignor to Signal Engineering & Manufacturing Company, New York, N. Y., a corporation of Massachusetts

Application February 1, 1930. Serial No. 425,327

3 Claims. (Cl. 177—7)

The present invention relates to an electrical device that will operate intermittently as long as it is energized with predetermined intervals between successive operations thereof, such a device being particularly adapted for sounding signals of various types.

The device of the present invention is particularly characterized by the fact that the intermittent operation thereof is brought about without the use of any electrical contact making devices, the device continuing its intermittent operation so long as it is energized with no interruptions in the flow of current to its energizing winding. Furthermore, the device is characterized by the fact that it is capable of ready adjustment so as to vary the length of the intervals between successive operations thereof. The above and other advantageous features will hereinafter more fully appear with reference to the accompanying drawings in which—

Fig. 1 is a view in front elevation of the device.

Fig. 2 is a vertical sectional view along the line 2—2 of Fig. 1, looking in the direction of the arrows.

Fig. 3 is a horizontal sectional view along the line 3—3 of Fig. 4, looking in the direction of the arrows.

Fig. 4 is a sectional view along the line 2—2 of Fig. 1 illustrating the parts of the device in different positions.

Fig. 5 is a sectional view similar to Fig. 4, further illustrating the operation of the device.

Fig. 6 is a fragmentary sectional view along the line 6—6 of Fig. 2.

Fig. 7 is a diagrammatic view illustrating a modification of the device.

Like reference characters refer to like parts in the different figures.

Referring first to Figs. 1 and 2, the device comprises a casing 1 inclosing and supporting a magnetic core 2 generally O-shaped in form, with an air gap at 3 in one leg 2a thereof. The longer portion of the leg 2a beyond the air gap 3 is surrounded by a winding 4 so that when the winding 4 is energized from any suitable source of alternating current, a pulsating magnetic field will be set up across the air gap 3.

A shaft 5 is rotatably supported in bearings 6 provided by opposed faces of the casing 1 and this shaft 5 carries a thin disk 7 of magnetic material. As best shown in Fig. 3, the axis 5 of the shaft 5 is parallel to the axis of the core

leg 2a and the diameter of the disk 7 is such that a peripheral portion of the disk 7 is always disposed within the air gap 3. Consequently, when the winding 4 is energized, from a source of alternating current the lines of force 60 passing through the peripheral portion of the disk 7, across the gap 3, will so react on the disk as to set up a torque tending to turn the shaft 5 at a substantially uniform speed for a given voltage and frequency of the alternating 65 current source. Obviously the rotation of the shaft 5 will continue so long as the winding 5 remains energized, and the manner in which the rotation of the shaft 5 can be utilized to automatically cause the intermittent operation 70 of the device will next be described.

As an illustrative embodiment of the invention, the casing 1 is shown mounted on a metallic gong 8, the periphery of which is adapted to be engaged by a striker 9 to sound the gong 75 8. The striker 9 is carried by a U-shaped frame 10, the spaced parallel sides of which extend upwardly on either side of the shaft 5 and are pivotally connected to arms 11 turnable on pivots 12 provided by the sides of the 80 casing 1. Two pairs of arms 11 are utilized for supporting the striker frame 10, so that the striker 9 will always remain in a substantially vertical position when the frame 10 is raised or lowered by pivotal movement of the arms 10. 85

As best shown in Figs. 1 and 4, the rotative movement of the shaft 5 is adapted to be translated into rectilinear movement of the striker frame 10 by means of a pin 13 carried at the free end of a lever 14 pivotally mounted between 90 the lower pair of arms 11. The pin 13 is adapted to fit in a spiral groove 15 formed on a sleeve 16 rotatable with the shaft 5, so that with the pin 13 engaged in the groove 15, as shown in Fig. 1, rotation of the shaft 5 will cause the 95 arms 11 to be swung upwardly about their pivots and impart a vertical movement to the striker frame 10. When the rotation of the shaft 5 has moved the arms 11 upwardly to the point where the pin 13 has nearly reached the upper end of the groove 15, a tail portion 17 of the lever 14 strikes a stationary stop 18, as shown in Fig. 4. When this occurs, the lever 14 is turned in a clockwise direction about its pivot 100 thereby withdrawing pin 13 from the groove 15, 105 whereupon, the arms 11 being unsupported, the frame 10 drops quickly to cause the striker 9 to hit the gong 8 a sharp blow.

The position of the striker 9 at the moment of hitting the gong 8 is shown in Fig. 5, and 110

as the frame 10 reaches the lower end of its stroke, the tail 17 of the lever 14 engages a second stationary stop 19 which serves to turn the lever 14 in a counterclockwise direction to 5 reengage the pin 13 with the spiral groove 15. Inasmuch as the weight of the frame 10 and striker 9 causes the tail 17 to strike the stop 19 with considerable force, on the down stroke of the frame 10, the stop 19 is preferably supported 10 by a resilient finger 20 bent around the shaft 5, as shown in Fig. 6, and secured to the casing 1 by screws 21 at a considerable distance from the stop 19. Consequently, the stop 19 is adapted to yield when struck by the tail 17, so that engagement with the stop 19 exerts no damping 15 effect on the stroke of the gong.

As previously pointed out, continued energization of the winding 4 causes continuous rotation of the disk 7 so that as soon as the pin 13 is reengaged with the spiral groove 15, as shown 20 in Fig. 5 the striker frame 10 starts to move upwardly again. The frame 10 is shown in an intermediate position in Fig. 1 in which the tail 17 is about midway between the controlling stops 18 and 19, and it is obvious that so long 25 as the winding 4 is energized, the device will continue to function and cause the striker 9 to sound the gong 8 at intervals. Obviously, the speed of rotation of the shaft 5 will generally determine the length of the periods between 30 strokes of the gong and with a predetermined speed of the shaft, this period is susceptible of wide variation by altering the position of the upper stop 18. To this end, the stop 18 is supported by a bracket 22 which, as best shown in 35 Figs. 1 and 6, extends upwardly parallel to the shaft 5 inside of the frame 10. The bracket 22 provides a slot 23 in which the stop 18 is slideable and is adapted to be clamped in different 40 positions by means of screws 24 cooperating with washers 25. Thus the stop can be raised and lowered readily so as to very closely control the length of the upward travel of the frame 10. In this manner the interval between successive 45 strokes of the gong 8 can be varied within a wide range and with great accuracy.

While the vertical movable frame 10 is shown 50 as carrying a striker 9 to cooperate with the gong 8, as one illustrative embodiment of the invention, obviously the intermittent up and down movement of the frame 10 can be utilized for other purposes without departing from the present invention. For example, as illustrated 55 diagrammatically in Fig. 7, the frame 10 may be employed to bridge the gap between spaced contacts 26 at the end of each stroke, so as to energize a series of suitable visual or audible signals, indicated at 27, from a suitable source of electrical energy, indicated at 28. Furthermore, the closing of the circuit between the 60 contacts 26 could also be employed in conjunction with sounding of the gong 8 by the striker 9 so as to set in operation other electrically controlled devices in circuit with the contacts 26, 65 sounding of the gong 8 being depended upon to call attention to the initiation of the operation of such devices. In any of the above described practical utilizations of my invention, the essential principle remains the same, namely, 70 the provision of an intermittently operating electrical device which will continue to operate automatically as long as it is energized without

necessitating the interruption of the energizing circuit.

I claim—

1. In an electrical signal device, a resonant member of the gong type, a frame centrally supported within the concave side of the gong, an induction motor of the disk rotor type mounted in said frame with its magnetic core secured to a vertical portion of said frame, a vertical shaft for said motor providing a spiral groove, a yoke embracing said motor and providing arms extending in parallel relation on opposite sides of said motor shaft, a gong hammer extending parallel to said motor shaft, means for pivotally securing the ends of said yoke arms to said frame and to said hammer respectively, a pawl pivotally mounted between said yoke arms, means for causing said pawl to engage the motor shaft groove so that said hammer will be raised upon rotation of the motor, and means for disengaging the pawl from said groove at a predetermined point in the upward movement of the pawl and hammer so that said hammer will fall to strike the gong. 85

2. In an electrical signal device, a resonant member of the gong type, a frame centrally supported within the concave side of the gong, an induction motor of the disk rotor type mounted in said frame with its magnetic core secured to a vertical portion of said frame, a vertical shaft 105 for said motor providing a spiral groove, a yoke embracing said motor and providing arms extending in parallel relation on opposite sides of said motor shaft, means for pivotally securing the ends of said yoke arms to said frame and to said hammer respectively, a pawl pivotally mounted between said yoke arms, means operable when said yoke supports said hammer with its end adjacent to said gong for engaging said pawl in said shaft groove so that the hammer 115 will be raised upon rotation of the motor, and means for disengaging the pawl from said groove at a predetermined point in the upward movement of the pawl so that the hammer will fall by gravity to strike said gong. 120

3. In an electrical signal device, a resonant member of the gong type, a frame centrally supported within the concave side of the gong, an induction motor of the disk rotor type mounted in said frame with its magnetic core secured to a vertical portion of said frame, a vertical shaft for said motor providing a spiral groove, a yoke embracing said motor and providing arms extending in a parallel relation on opposite sides of said motor shaft, a gong hammer extending 130 parallel to said motor shaft, means for pivotally securing the ends of said yoke arms to said frame and to said hammer respectively, a pawl pivotally mounted between said yoke arms, means operable when said yoke supports said 135 hammer with its end adjacent to said gong for engaging said pawl in said shaft groove so that the hammer will be raised upon rotation of the motor, and means for disengaging the pawl from said groove at a predetermined point in the upward movement of the pawl so that the hammer will fall by gravity to strike said gong, said pawl 140 disengaging means being vertically adjustable so as to control the distance through which said hammer falls. 145

CHARLES LUDWIG HANEL.
